BABY TOILET TRAINER

Gladys M. Cantrell, 104 S. Johnson St.,
Alvin, Tex. 77511

Filed Apr. 6, 1967, Ser. No. 6,545

Term of patent 14 years

(Cl. D23—53)

FIG. 1 is a front perspective view of a baby toilet trainer, showing my new design; and

FIG. 2 is a rear perspective view thereof.

I claim:

The ornamental design for a baby toilet trainer, as shown.
